UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,221,115.

Specification of Letters Patent.

Patented Apr. 3, 1917.

Application filed March 13, 1915. Serial No. 14,124.

To all whom it may concern:

Be it known that I, HENRY G. VOIGHT, a citizen of the United States, residing in New Britain, county of Hartford, and State of Connecticut, have invented certain new and useful Improvements in Locks, of which the following is a full, clear, and exact description.

This invention relates to locks, and more especially to locks for corridor doors of hotels. In certain aspects of the invention, my improvements are directed particularly to a so-called two-bolt lock of the general type illustrated in the Carroll Patent No. 898,434, issued to Sargent & Company on September 15, 1908, but in certain phases of the invention the improvements are applicable to a lock with a single dead bolt.

In the two-bolt hotel lock of the type above indicated, the customary bitted or winged keys have usually been employed. When the inside bolt is protracted by the occupant of the room, the maid's key cannot operate the outside bolt (for the purpose of retracting the inside bolt through the lever connection), owing to the fact that when the inside bolt is protracted, a ward or other key blocking member is moved into operative relation with respect to the outside keyhole, so as to prevent all of the keys, except the emergency key, from operating the lock from the outside.

One of the primary objects of the present invention is to provide means for blocking the operation of the maid's key, and other keys of low order, from the outside of the door, under the conditions noted, in the case where the outside bolt is operated by a master keyed cylinder lock, or pin tumbler mechanism, with its associated keys, instead of by the customary bitted keys acting directly on the bolt.

Another object of the invention is to provide a two-bolt lock, in which one of the keys, which may be termed the emergency key, is operative to actuate and release the tumbler mechanism of the inside bolt, when said bolt is in protracted position, and when said key is inserted into the pin tumbler mechanism, at the outside of the door, so that when the outside bolt is protracted by said key, the inside bolt will be retracted through the well-known lever connection, after which the outside bolt can be retracted independently, the tumbler of the inside bolt

being inoperative, however, under such conditions, by means of the other key or keys. In other words, the pin tumbler mechanism at the outside of the door is so arranged with respect to the tumbler of the inside bolt that when the inside bolt is protracted, it can be retracted by the emergency key but not by the other key or keys.

Another object of the invention is to provide an improved shut-out mechanism applicable to a dead bolt so that when the bolt has been protracted by a key of high order, it cannot be retracted by a key of lower order.

I also aim to provide an improved form of tumbler mechanism for a dead bolt operable by a plurality of keys; to furnish an improved form of cylinder lock of the master-keyed type; and to generally improve the construction and operation of devices of the class to which my invention relates.

In the accompanying drawings,

Figure 1 is an elevation of a lock embodying my improvements, with the cap plate omitted, both dead bolts being in the retracted position.

Fig. 2 is a reverse view of Fig. 1, partly in section.

Fig. 3 is a view similar to Fig. 1, showing the inside bolt protracted and the outside pin tumbler mechanism partly actuated by the master (maid's) key.

Fig. 4 is a view of the upper portion of the lock, showing the outside bolt partially protracted, and the inside bolt partially retracted, by the emergency key.

Fig. 5 shows the outside bolt projected by the change key, with the tumbler connector omitted.

Fig. 6 is a view similar to Fig. 5, showing the outside bolt protracted by the emergency or shut-out key.

Fig. 7 is a section on line 7—7 of Fig. 1, with the master (maid's) key inserted into the outside pin tumbler mechanism.

Fig. 7^A is a fragmentary view of Fig. 7 with the rollbacks turned through one hundred and eighty degrees.

Fig. 8 is a section on line 8—8 of Fig. 4.

Fig. 9 comprises rear face views of the tumblers of the outside bolt.

Fig. 10 is a detail prospective view of the tumbler connector; and

Fig. 11 is a detail of the change key.

In the drawings, I have shown my im-

provements applied to a two-bolt lock in which the bolts are actuated by inside and outside cylinder locks respectively. It may be stated, however, that the operation of the inside bolt by means of a cylinder lock is, for the most part, entirely immaterial to the invention, inasmuch as the inside bolt can be actuated by a thumb turn hub, or like member, if desired. Furthermore, it is not essential in all aspects of the invention that the outside bolt be actuated by a cylinder lock, and, as previously intimated, certain features of my improvements are applicable to a lock having a single dead bolt protractable from either side of the door.

In the particular form shown, the case 20 has a face plate or front 21, with openings for dead bolts 22 and 23 respectively, and a latch bolt 24. The bolt 22 may be operated from the outside of the door by a cylinder lock 25 having the usual pin tumblers, and the bolt 23 may be actuated from the inside of the door by a second cylinder lock 26 (Fig. 2). The bolts 22, 23 will be referred to as the outside and inside bolts respectively, and in the particular form shown, the outside bolt is arranged above the inside bolt, and the latter is in turn located above the latch bolt 24. When the inside bolt is protracted, it actuates an elbow lever 27 to dog the yoke or shoe 28 by means of which the latch bolt is retracted, thereby blocking the rotation of the outside knob, and thus giving an indication that the room is occupied.

The inside bolt 23 is provided with talons 29 adapted to be engaged by the dog or rollback 30 of the inside cylinder 26, and said bolt is further provided with a single tumbler 31 pivoted thereon at 31^a, and having a projection 32 located between said talons. The tumbler 31 also has a lug 33 adapted to engage the front or rear face of the usual stump or fence 34 cast on the back of the case. A blocking device 35 is associated with the cylinder lock 26 for the purpose of preventing the withdrawal of the key when the bolt 23 is protracted, and in the form shown, the blocking device 35 consists of a lever pivoted on a post 36 on the case. The lever 35 has one end interposed between projections 37 on the tumbler 31, so that as the bolt is protracted, as shown in Fig. 3, the other end of the lever 35 is swung into the path of the rollback 30, while when the bolt is retracted the blocking lever is swung out of the path of said rollback. The inside bolt 23 is adapted to be retracted when the outside bolt 22 is protracted, owing to the provision of a connecting lever 38, which is pivoted on a post 39, and connects the bolts in the manner described in the Carroll Patent No. 898,434.

Referring now to the outside bolt 22, the same is provided with talons 40 adapted to

be engaged by a rollback of the outside cylinder lock 25, as hereinafter described. This outside bolt is also provided with a plurality of tumblers adapted to coöperate with said cylinder lock, and in the form shown, these tumblers are two in number, as indicated at 41 and 42, respectively. Both of these tumblers are pivoted on the bolt itself by means of a single pivot pin or post 43, and the tumbler 42 has a projection 44 disposed between the talons 40 of the bolt, while the tumbler 41 has a projection 45 disposed between said talons. The tumbler 41, which is located beneath the tumbler 42, is provided with a projection 46 to coöperate with a stump or fence 47 cast on the back of the case, and it is further provided with a notch 48 adapted to be engaged by a projection 49 on the tumbler 42. The projection 49 is so arranged relatively to the notch 48 that the tumbler 41 is depressed with and by the tumbler 42, when the latter is depressed by the pin tumbler mechanism, although, on the other hand, the tumbler 41 can be depressed independently of the tumbler 42. For purposes of description, I shall refer to the tumbler 41 as the ordinary or primary tumbler, inasmuch as it is actuated in the same way by all of the keys of the pin tumbler mechanism 25, and I shall refer to the tumbler 42 as the auxiliary or emergency tumbler. Instead of having a rigid shoulder or abutment to coöperate with the fence 47, the emergency tumbler 42 is provided with a special movable abutment 50 which coöperates with said fence in the manner herein-after described. The member 50 is pivoted on the tumbler 42, at 51, and is normally held in the position shown in Fig. 6 by a spring 52. This spring tends to turn the member 50 about its axis, and holds one end in snug engagement with a small projection 53 on the tumbler 42. When the tumbler 42 is given a full actuation on the protracting movement of the bolt 22, the movable member or abutment 50 is swung bodily with the tumbler 42 so as to interlock with the fence 47, in the manner shown in Fig. 6. This deadlocks the bolt in its protracted position, and it will be understood, of course, that in this position of the parts, the primary tumbler 41 deadlocks the bolt in the usual manner by means of the projection 46, which engages the fence 47 behind the member 50. When, however, the emergency tumbler 42 is given only a partial actuation, that is, when it is depressed only part way, the member 50 is swung on its pivot 51, into the position shown in Fig. 5, by the engagement of said member 50 with one face of the fence. In this position, the member 50 obviously has no function in preventing the withdrawal of the bolt.

It will be manifest that while, under certain circumstances, the movable member 50

prevents the retraction of the outside bolt, it does not at any time prevent the protraction of said bolt, this latter function being confined to the lug 46 on the primary tumbler 41, which lug co-operates with the front and rear faces of the fence 47 in the customary manner.

When the cylinder lock 25 is actuated by a change key, master key, or other key of low order, for the purpose of protracting the outside bolt, the emergency tumbler 42 is only given a partial depression so that when the bolt is fully protracted, it is deadlocked in that position by the lug 46 of the primary tumbler but not by the movable member 50 of the emergency tumbler. On the other hand, when the outside bolt is protracted by the emergency key, the emergency tumbler is fully depressed, and the member 50 is moved into locking position with respect to the fence. In this position, the member 50 is not releasable by the keys of lower order for the reason that the latter cannot depress the emergency tumbler to a sufficient extent, and therefore the emergency key serves as a shut-out key.

In order to achieve the results just specified, the outside cylinder lock 25 is preferably constructed in the following manner: The case 25^a contains a key plug 54 surrounded by an eccentric sleeve 55, and the key plug and sleeve are adapted to be locked to the case by the customary pin tumblers 56. The arrangement is such that at least one key will rack the pin tumblers so as to rotate the key plug individually, while at least one key will rack the pin tumblers so as to rotate the key plug and sleeve together. In this last case, of course, the key plug rotates on the axis of the sleeve rather than its own axis, and it is to be noted that the axis of the sleeve is disposed somewhat above the axis of the key plug. A dog, cam or rollback 57 is secured to the rear end of the key plug by screws 58, and is provided with a radial arm carrying a projection 59 for engaging the projection 44 of the emergency tumbler. Another dog or rollback 60 is adapted to rotate on the axis of the sleeve 55, and includes a ring-like body portion having an arm 61, with side flanges 62, between which the arm of the emergency rollback 57 is confined. In the present case, therefore, the rollback 60, which may be termed the regular or ordinary rollback, is loose from the sleeve and rotates freely thereon, and the operating movement of said rollback is imparted to it by the interlocking with it of the arm of the emergency rollback, as described, it being understood that the emergency rollback being fixed to the key plug, is rotatable by all of the keys adapted to the lock. The interlocking of the arm of the emergency rollback between the flanges 62 of the regular rollback per-

mits independent radial movement of said rollbacks when the key plug rotates on its own axis, instead of on the axis of the sleeve, as will be understood. The arm 61 of the regular rollback 60 is adapted to engage the talons 40 of the bolt 22 in the usual manner, and also to engage the projection 45 of the primary tumbler 41; while the projection 59 of the emergency rollback, as previously stated, engages the projection 44 of the emergency tumbler, and thereby either actuates the emergency tumbler to its full extent, as shown in Fig. 4, or only partially, as shown in Fig. 5. If the change key 63 (Fig. 11), master (maid's) key 64 (Fig. 7), or grand master key (not shown) be used to actuate the cylinder lock 25, the key plug and sleeve are locked together, so that the emergency rollback rotates on the axis of the sleeve, and therefore the emergency rollback in protracting the bolt gives the emergency tumbler an incomplete actuation, as shown in Fig. 5. If, however, the emergency key 65 is used, this will rotate the key plug individually about its own (lower) axis, thereby carrying the emergency rollback down far enough to give the emergency tumbler a full actuation, as shown in Fig. 6. It will be readily understood, therefore, that when the bolt has been protracted by the emergency key, as shown in Fig. 6, it cannot be retracted by any of the other keys, inasmuch as said other keys rotate the emergency rollback on a higher axis, so that it will not carry down the emergency tumbler to an extent sufficiently to liberate the movable member 50 thereof from the fence 47. On the other hand, when the bolt is protracted by any of the keys of lower order in the position shown in Fig. 5, it may readily be retracted by any of said keys, or by the emergency or shut-out key.

The tumbler mechanism of the inside bolt is connected with that of the outside bolt in such a manner that when the bolts occupy the relative positions shown in Fig. 3, the cylinder lock 25 will be incapable of releasing the tumbler 31 of the inside bolt, it being understood, of course, that in order to retract the inside bolt from the outside its tumbler must be released and the outside bolt must be protracted. In the form shown, the tumbler mechanism of the lower bolt is connected with the tumbler mechanism of the upper bolt by means of a connector 66 which may have the form shown in detail in Fig. 10. This tumbler connector is in the nature of a slide having openings at the respective ends by which it is guided vertically of the case on the respective fences 34 and 47. At its lower extremity, the connector has a lip 67, taking into a slot 68 in the tumbler 31 of the inside bolt. At its upper end, the connector has a lip 69 overlying the upper edge of the emergency tumbler, and a

lip 70 extending beneath the lower edge of said emergency tumbler. The connector interconnects the tumbler mechanisms irrespective of the relative positions of the bolts and the tumblers slide freely beneath the connector as the bolts are protracted and retracted.

The operation of the lock is substantially as follows: Assuming the parts to be in the position shown in Fig. 1, if the guest wishes to lock his room against intrusion, he protracts the inside bolt 23 by means of the cylinder lock 26. In this operation, the knob is dogged, as previously described, and the slot 68 permits the tumbler 31 to move freely with respect to the tumbler connector. It will be observed that in this position of the parts, the outside bolt 22 is locked against protraction by means of the connecting lever 38, unless the inside bolt is released for retraction, and if the outside cylinder lock is actuated by one of the keys of lower order, the tumbler of the inside bolt will not be released, owing to the fact that the emergency tumbler 42, in abutting the lip 70 of the tumbler connector, will not carry down the tumbler connector sufficiently far to release the inside bolt. If, however, the emergency key be inserted in the outside cylinder lock and rotated, the emergency rollback 57 will rotate on a lower axis, and will carry down the emergency tumbler and the connector to a sufficient extent for releasing the tumbler 31, whereupon the outside bolt may be protracted and the inside bolt simultaneously retracted. The outside bolt is then retracted independently, and the door is unlocked. If it is desired to lock any one out of the room, the proprietor can use the emergency key as a shut-out key, inasmuch as the keys of lower order are incapable of releasing the outside dead bolt after it has been thrown by the emergency key, as previously explained.

I have not attempted to describe the numerous modifications of the construction which may be adopted, without departing from the scope of the invention as defined in the claims.

I do not claim herein the cylinder lock mechanism *per se*, as the same forms the subject matter of my application Serial No. 65058, filed December 4, 1915.

What I claim is:—

1. In a lock, the combination of an inside bolt, an outside bolt, a lever connecting said bolts, a tumbler for the inside bolt, at least two tumblers for the outside bolt, means of connection between one of said last named tumblers and the tumbler of the inside bolt, means for operating the inside bolt, and means for operating the outside bolt including a key for releasing the tumbler of the inside bolt by said means of connection, and another key for said outside bolt in-

operative to release the tumbler of said inside bolt; substantially as described.

2. In a lock, the combination of two bolts, a single tumbler carried by one of said bolts, a plurality of tumblers carried by the other bolt, a fence to coöperate with the first tumbler, a fence to coöperate with said plurality of tumblers, means for operating the bolt having said single tumbler, means of connection between said single tumbler and one of the tumblers of the other bolt, and a cylinder lock mechanism for operating such other bolt having a key for releasing said single tumbler by said means of connection, and another key which is incapable of releasing said single tumbler; substantially as described.

3. In a lock, the combination of an outside bolt, a fence, a plurality of tumblers for said bolt coöoperating with said fence, a plurality of keys, a cylinder lock mechanism operated by one of said keys to give both of said tumblers complete actuations with respect to said fence, said cylinder lock mechanism when operated by another key being incapable of giving one of said tumblers a complete actuation, a tumbler connector actuated by said last named tumbler, and an inside bolt having a tumbler operatively connected with said tumbler connector; substantially as described.

4. In a lock, the combination of a bolt, a tumbler therefor, a tumbler connector for operating said tumbler, a second bolt having a plurality of tumblers, one of said tumblers adapted to actuate said tumbler connector and thereby the tumbler of said first bolt, a plurality of keys, and a cylinder lock mechanism adapted for actuation by said keys and constructed to depress to different degrees the tumbler of said second bolt which actuates said tumbler connector as different keys are used; substantially as described.

5. In a lock, the combination of an inside bolt, a tumbler therefor, a fence coöoperating with said tumbler, a member connected with said tumbler to release the same from said fence, an outside bolt, a lever connection between said bolts, a plurality of tumblers for the outside bolt, one of said last-named tumblers adapted to actuate said tumbler-releasing member, two keys, and a cylinder lock mechanism adapted for actuation by said keys to protract and retract the outside bolt, said cylinder lock mechanism constructed to release the tumbler of the inside bolt by said releasing member as one of said keys is used, and being incapable of actuating said releasing member to release the tumbler of the inside bolt when another of said keys is used; substantially as described.

6. In a hotel lock, the combination of an inside bolt, a tumbler therefor, a member for releasing said tumbler, an outside bolt, a

- lever connection between said bolts, a plurality of tumblers for said outside bolt, one of said last-named tumblers connected with said tumbler-releasing member to actuate the same, two keys, a cylinder lock adapted for actuation by said keys, and a plurality of rollbacks on said cylinder lock operable by both of said keys to protract and retract the outside bolt, one of said rollbacks being arranged to depress said last-named tumbler and thereby actuate said tumbler-releasing member to release the inside bolt when the cylinder lock is actuated by one key, said rollback being incapable of depressing said tumbler to a sufficient extent to release the tumbler of the inside bolt when the other key is used in connection with said cylinder lock; substantially as described.
7. In a lock, the combination of an inside bolt, an outside bolt, a lever connecting said bolts, tumblers for the respective bolts, a tumbler connector for operating one tumbler by means of another, a key operative on one bolt to release the other bolt by means of the tumbler connector when the bolts have a certain relation to each other, and another key inoperative on said tumbler connector when the bolts have such relation to each other; substantially as described.
8. In a lock, the combination of an inside bolt, an outside bolt, a lever connection between said bolts, tumblers for the respective bolts, a tumbler connector, means for operating the inside bolt, a pin tumbler lock for operating the outside bolt, and a plurality of keys fitted to said pin tumbler lock, said tumbler connector being operative by one of said keys when the bolts occupy a predetermined relation to each other, but not by another of said keys; substantially as described.
9. In a lock, the combination of a boltage mechanism having two sets of tumblers, a tumbler connector connecting said sets of tumblers, a plurality of keys, and a pin tumbler lock for said keys adapted to operate said tumbler connector by means of one key but not by means of another key; substantially as described.
10. In a lock, the combination of a dead bolt, a fence, two tumblers fixedly pivoted to and carried by said dead bolt and co-operating with said fence, a key for giving one of said tumblers a complete actuation with respect to said fence, and for giving the other tumbler an incomplete actuation with respect to said fence, and a second key for giving both of said tumblers complete actuations with respect to said fence; substantially as described.
11. In a lock, a dead bolt, a tumbler carried thereby, a movable member mounted on said tumbler, a cylinder lock, a key for said cylinder lock adapted to protract said bolt and swing said movable member into locking engagement with said fence on the protraction of the bolt, and another key for said cylinder lock adapted to protract the bolt but inoperative to swing said movable member into locking engagement with said fence upon the protraction of the bolt; substantially as described.
12. In a lock, the combination of a dead bolt, a fence, a pivoted tumbler carried by said bolt, a member movably mounted on said tumbler to co-operate with said fence, a key for swinging said tumbler and protracting said bolt and throwing said movable member into locking engagement with said fence on the protraction of said bolt, and another key adapted to protract the bolt but inoperative to interlock said movable member with said fence on the protraction of the bolt; substantially as described.
13. In a lock, a dead bolt, a fence, a pivoted tumbler carried by the bolt, a movable spring pressed member carried by the tumbler to co-operate with said fence, a cylinder lock, a key for said cylinder lock adapted to swing said tumbler and protract the bolt and shift said movable member into locking engagement with said fence to deadlock the bolt in protracted position, and another key for said cylinder lock adapted to protract said bolt but inoperative on said tumbler to a sufficient extent to deadlock the bolt in protracted position; substantially as described.
14. In a lock, the combination of a dead bolt, a fence, a plurality of tumblers, and means for fixedly pivoting said tumblers to said dead bolt, one of said tumblers having a rigid shoulder or abutment to co-operate with said fence, and another tumbler having a movable shoulder or abutment to co-operate with said fence, and means for actuating said tumblers and protracting and retracting the bolt; substantially as described.
15. In a lock, the combination of a dead bolt, a fence, two tumblers fixedly pivoted to said bolt so as to be carried thereby, one of said tumblers having a rigid shoulder or abutment to co-operate with said fence, the other tumbler having a movable shoulder or abutment to co-operate with said fence, said last-named tumbler when actuated adapted to depress and actuate said first tumbler, and a cylinder lock for operating said tumblers; substantially as described.
16. In a lock, the combination of a dead bolt, a primary tumbler therefor having a fixed shoulder or abutment, an emergency tumbler for said bolt having a movable shoulder or abutment, means co-operating with said shoulders or abutments to deadlock the bolt by both of said tumblers when the latter are given full actuations, said emergency tumbler adapted to actuate said primary tumbler, two keys, and a cylinder

lock operable by one key to depress the emergency tumbler sufficiently to give it a full actuation, said cylinder lock inoperative to give said emergency tumbler a complete actuation when the other key is used; substantially as described.

17. In a lock, the combination of an inside bolt, an outside bolt, tumblers for the outside bolt, a key for giving said tumblers complete actuations, another key for giving at least one of said tumblers an incomplete actuation, a tumbler for the other bolt operatively connected with said last-named tumbler so that the tumbler of such other bolt is given a complete or an incomplete actuation according to the key used, and means for interconnecting said bolts so that they move in opposite directions; substantially as described.

18. In a lock, the combination of a dead bolt, a fence, a plurality of tumblers, one of said tumblers having a rigid shoulder or abutment, the other tumbler having a movable shoulder or abutment, both of said shoulders or abutments to coöperate with said fence; substantially as described.

19. In a lock, the combination of a boltage mechanism having two tumblers, one of said tumblers having a rigid shoulder or abutment, the other tumbler having a movable shoulder or abutment, a fence to coöperate with said tumblers, a cylinder lock having a rollback to operate one of said tumblers, and a second rollback on said cylinder lock to operate the other tumbler; substantially as described.

20. In a lock, the combination of a boltage mechanism having two tumblers and a fence, a cylinder lock having a rollback to operate one of said tumblers and cause it to interlock with said fence, and a second rollback on said cylinder lock to operate both of said tumblers and cause both of them to interlock with said fence; substantially as described.

21. In a lock, a dead bolt, a fence, a primary tumbler for said bolt coöperating with said fence, a shutout tumbler for said bolt, a movable shut-out device carried by said shut-out tumbler and coöperating with said fence and constructed to block the retraction of the bolt when said shut-out tumbler is shifted to a predetermined extent on the protraction of the bolt, a plurality of keys, and a cylinder lock mechanism for operating said bolt by means of said keys constructed to shift said shut-out tumbler to such predetermined extent when actuated by one but not by another of said keys; substantially as described.

22. In a lock, a dead bolt, a plurality of pivoted tumblers carried thereby, an abutment on each tumbler, fence portions on the lock case adapted to coöperate with the respective abutments to deadlock the bolt

in the protracted position, a cylinder lock, a key for said cylinder lock adapted to move both abutments into interlocking engagement with the respective fence portions, and another key for said cylinder lock adapted to interlock one of said abutments with its fence portion but inoperative to interlock the abutment on the other tumbler with its fence portion; substantially as described.

23. In a lock, a dead bolt, a fence, a primary tumbler for said bolt coöperating with said fence, a shut-out tumbler coöperating with said fence to block the retraction of said bolt when said shut-out tumbler is shifted to a predetermined extent on the protraction of the bolt, a cylinder lock mechanism having a primary rollback to coöperate with said primary tumbler, and an emergency rollback to coöperate with said shut-out tumbler, and a plurality of keys for said cylinder lock mechanism, said cylinder lock mechanism constructed to shift said shut-out tumbler to the aforesaid predetermined extent by means of said emergency rollback when one of said keys is used, and to shift said shut-out tumbler to a less extent when another key is used; substantially as described.

24. In a lock, a dead bolt, a fence, tumbler mechanism including a tumbler which co-
operates with said fence to act as a shut-out
device when said tumbler is shifted to a
predetermined extent on the protraction of
the bolt, a plurality of keys, and a cylinder
lock mechanism constructed to shift said
tumbler to different extents as said mecha-
nism is actuated by different keys respec-
tively; substantially as described.

25. In a lock, a dead bolt, a fence, a tumbler for said bolt coöperating with said fence to act as a shut-out device when said tumbler is given a predetermined throw or movement, a plurality of keys, and a cylinder lock mechanism operable by said keys to protract the bolt and constructed to give said tumbler two different throws as different keys are used; substantially as described.

26. In a lock, a bolt, a fence, a variable throw tumbler to coöperate with said fence, a variable throw cylinder lock mechanism for operating said tumbler, and a plurality of keys for actuating said bolt through said cylinder lock mechanism, said cylinder lock mechanism so constructed and arranged that one of said keys causes said tumbler to interlock with said fence so as to shut out the other keys; substantially as described.

27. In a lock, the combination of a case and boltage mechanism therein involving a pair of upper tumblers, a lower tumbler, and a tumbler connector connecting the lower tumbler with one of the upper tumblers, a key for operating the other upper tumbler without fully actuating the tumbler to which said connector is con- 125
130

nected, and a second key for operatively actuating all of said tumblers concurrently; substantially as described.

28. In a lock, the combination of a case, 5 a boltage mechanism therein having a pair of upper tumblers, and a single lower tumbler, a tumbler connector in the form of a vertically movable part connecting one of the upper tumblers with the lower tumbler, a cylinder lock, a key for said cylinder lock, adapted to operate the upper tumblers concurrently and simultaneously oper-

ate the lower tumbler through said tumbler connector, and a second key for operating the upper tumbler which is free from said 15 tumbler connector without actuating said connector; substantially as described.

In witness whereof, I have hereunto set my hand on the 11th day of March, 1915.

HENRY G. VOIGHT.
